(57) **CLAIM**

The ornamental design for a firearm as shown and described.

DESCRIPTION

FIG. 1 is a top perspective view showing an embodiment of the firearm of Applicants' invention.

FIG. 2 is a bottom perspective view of the embodiment of the firearm of Applicant's invention.

FIG. 3 is a left side view of the embodiment of the firearm of Applicant's invention.

FIG. 4 is a right side view of the embodiment of the firearm of Applicant's invention.

FIG. 5 is a front view of the embodiment of the firearm of Applicant's invention.

FIG. 6 is a back view of the embodiment of the firearm of Applicant's invention.

FIG. 7 is a top view of the embodiment of the firearm of Applicant's invention.

FIG. 8 is a bottom view of the embodiment of the firearm of Applicant's invention.

FIG. 9 is a top perspective view showing an alternative embodiment of the firearm of Applicants' invention.

FIG. 10 is a bottom perspective view of the alternative embodiment of the firearm of Applicant's invention.

FIG. 11 is a left side view of the alternative embodiment of the firearm of Applicant's invention.

FIG. 12 is a right side view of the alternative embodiment of the firearm of Applicant's invention.

FIG. 13 is a front view of the alternative embodiment of the firearm of Applicant's invention.

FIG. 14 is a back view of the alternative embodiment of the firearm of Applicant's invention.

FIG. 15 is a top view of the alternative embodiment of the firearm of Applicant's invention.

FIG. 16 is a bottom view of the alternative embodiment of the firearm of Applicant's invention.

FIG. 17 is a top perspective view showing an alternative embodiment of the firearm of Applicants' invention.

FIG. 18 is a bottom perspective view of the alternative embodiment of the firearm of Applicant's invention.

FIG. 19 is a left side view of the alternative embodiment of the firearm of Applicant's invention.

FIG. 20 is a right side view of the alternative embodiment of the firearm of Applicant's invention.

FIG. 21 is a front view of the alternative embodiment of the firearm of Applicant's invention.

FIG. 22 is a back view of the alternative embodiment of the firearm of Applicant's invention.

FIG. 23 is a top view of the alternative embodiment of the firearm of Applicant's invention.

FIG. 24 is a bottom view of the alternative embodiment of the firearm of Applicant's invention.

FIG. 25 is a top perspective view showing an alternative embodiment of the firearm of Applicants' invention.

(Continued)

FIG. 26 is a bottom perspective view of the alternative embodiment of the firearm of Applicant's invention.
 FIG. 27 is a left side view of the alternative embodiment of the firearm of Applicant's invention.
 FIG. 28 is a right side view of the alternative embodiment of the firearm of Applicant's invention.
 FIG. 29 is a front view of the alternative embodiment of the firearm of Applicant's invention.
 FIG. 30 is a back view of the alternative embodiment of the firearm of Applicant's invention.
 FIG. 31 is a top view of the alternative embodiment of the firearm of Applicant's invention; and,
 FIG. 32 is a bottom view of the alternative embodiment of the firearm of Applicant's invention.
 The broken lines in the figures are used to represent subject matter that forms no part of the claimed design.
